AERODYNAMIC SURFACE FOR DIRIGIBLE BOMBS

Ralph D. Wyckoff, Pittsburgh, Pa., assignor to
Gulf Research & Development Company, Pittsburgh, Pa., a corporation of Delaware

Application May 31, 1946, Serial No. 673,373

5 Claims. (Cl. 102—3)

1. This invention relates to aerodynamic surfaces for a dirigible or directionally controlled bomb and is particularly concerned with such surfaces which provide roll stability at all times even while the bomb is executing controlling or steering maneuvers.

In the operation of bombs which are not merely released but subsequently maneuvered or steered to their target, one must provide essentially two-dimensional control. Thus, in general, one must provide range control and azimuth control, steering in these two directions being accomplished by the use of appropriately connected rudders or elevators. These rudders or elevators may be controlled in a variety of ways; usually either 10 remotely through the use of radio, or automatically by the use of self-contained target-seeking apparatus. It is obviously necessary to maintain the above-mentioned two directional axes on the bomb at a definite orientation with respect to similar axes on the surface of the ground in order to properly isolate the functions of rudders and elevators for steering in azimuth or range, respectively. Rudders may be used to steer the bomb to the left or right in azimuth by 15 means of their operating mechanisms and similarly elevators may be used to control the bomb upward or downward in range through similar or auxiliary apparatus. The rudder and elevator operating mechanisms per se do not form the 20 subject matter of this invention and are therefore not described in detail. Examples of such mechanisms may be found in copending application by Wyckoff, Molnar, Palmer and Blewett, now U. S. Patent 2,466,528; and also in copending application by Wyckoff, Fitzwilliam and Salvetti, now U. S. Patent 2,495,304.

Deviation of the path of the bomb is accomplished by the application thereto of so-called aerodynamic lift surfaces. These surfaces serve the function of setting up aerodynamic forces approximately normal to the line of flight of the bomb so as to deflect its path in the desired direction. The attitude of these surfaces in the wind stream which is experienced by the falling bomb is controlled by the action of the aforementioned rudders and elevators. The term "lift" is here used in the general aerodynamic sense and is not restricted to vertical or gravitational lift.

The lift surfaces produce the required forces to deviate the path of the bomb in the following manner. When the plane of a symmetrical airfoil is parallel to the wind stream, no lift is produced, but when the airfoil cord presents an angle

to the direction of the wind stream (an angle of attack), then lift forces are generated which are at right angles to the wind stream. Alternatively, by the use of relatively small flaps at the trailing edge of an airfoil surface, the effective angle of attack of the airfoil may be controlled. A stabilizing tail surface is usually applied to a bomb in order to produce the weather-cock stability effect necessary to keep the axis of the bomb headed into the wind stream and keep the bomb from tumbling in flight. By the use of control flaps on the trailing edge of the stabilizing tail surfaces, aerodynamic forces may be set up which produce a yawing moment. This yawing moment applied at the rearward portion of the bomb serves to maintain the entire bomb axis at a stable angle of attack with respect to the wind stream, so that the lift surfaces fixed to the bomb may provide the desired aerodynamic lift component manifested as a side thrust which will deflect the path of the bomb in the desired direction.

Lift surfaces for bombs have heretofore usually been in the form of a flat-fin cruciform structure at the tail of the bomb. It has been found in wind tunnel as well as in actual drop tests that if a bomb with the usual flat-fin cruciform structure is given an attitude of both yaw and pitch with respect to the air stream for the purpose of producing a desired deviation in the line of flight, there results a tendency for the bomb to rotate on its axis, this rotation being due to the asymmetric aspect of the structure close to the bomb body when viewed from the direction of flight or wind stream. An elementary explanation of this effect may be found in the fact that a flat-fin cruciform structure presents a varying projected area to the wind stream if it is rotated about an yawed longitudinal axis, and the bomb tends to roll into a position which projects the greatest area to the wind stream. In addition, it will be found that a cruciform-fin structure inherently involves strong roll asymmetry due to the shading effect of the surfaces in one plane on those in the other plane when the cruciform-type structure is subjected to combined yaw and pitch angles of attack. This rotation must be prevented or controlled in order to maintain the rudders and elevators in their respective orientations.

In order to maintain the operation of rudders and elevators in their respective directions, it is obviously necessary to eliminate or avoid rotation of the bomb about its longitudinal axis, since any such rotation would result in confusion.

functions between the rudders and elevators. Numerous tests have demonstrated that while stabilizing ailerons located radially of the longitudinal axis are highly efficient for eliminating roll torques by reason of the substantial inter torques available, ordinary cruciform t-fin two component elevator and rudder arrangements produce in addition to the desired lateral deflection of the bomb, roll torques of such magnitude as to exceed the stabilizing capacity of the ailerons.

This invention is based on the discovery that a control surface having cylindrical symmetry may be used as a lift surface on such a bomb, and will produce little or no rotation even though given an attitude of considerable yaw and pitch either singly or both together. In its simplest form, this invention comprises the use of a lift surface for a dirigible bomb, said lift surface having cylindrical symmetry with respect to the axis of the bomb and having a cylindrical form as near cylindrical in form as practical limitations permit. The advantages of such a cylindrical control surface in eliminating roll torque have not heretofore been appreciated.

It is accordingly an object of this invention to provide a control surface for a controllable bomb in which the control surface is so shaped and oriented as to produce inappreciable roll torque in the bomb during its flight.

Another object of the invention is to provide a steerable bomb a control surface disposed and spaced in such manner as to have circular cylindrical symmetry about the bomb axis.

Another object of this invention is to provide a control surface for a bomb steerable in two components and in which inequality of the steering effect of any one of a plurality of control surfaces for deflecting the bomb will not produce appreciable roll torque on the bomb in flight.

Another object of this invention is to provide a remotely controlled bomb a control surface having cylindrical symmetry about the axis of the bomb.

These and other objects will be apparent from the following specification of which the drawings are a part and in which

Fig. 1 is a diagram of a bomb having the usual cruciform flat-fin tail structure;

Fig. 2 shows the bomb of Fig. 1 in a deflected attitude and illustrates its asymmetrical aspect to the wind;

Fig. 3 shows a control surface having circular cylindrical symmetry as contemplated by my invention;

Fig. 4 shows a diagram of a lift surface having circular cylindrical symmetry used together with a steering surface also having circular cylindrical symmetry;

Fig. 5 shows another disposition of control surfaces having cylindrical symmetry;

Figs. 6 and 7 show a form of the invention in which the control surface has circular cylindrical symmetry and in which the steering surfaces are mounted on the radial supports thereof;

Figs. 8 and 9 show a form of the invention in which the control surface has octagonal cylindrical symmetry and in which rudders, elevators, and ailerons are disposed in an alternative preferred manner;

Figs. 10 and 11 show a form of the invention in which a lift surface having circular symmetry is used together with a rudder, elevator, and aileron assembly having octagonal cylindrical symmetry;

Figs. 12 and 13 show a form of the invention in which both lift and steering surfaces have octagonal cylindrical symmetry.

Referring to Fig. 1, numeral 10 represents the body of a bomb and having cruciform tail fins 11, usually four in number, and each having aerodynamic flaps connected through mechanical linkages to a steering mechanism housed in body 10 or in the tail structure connected thereto. One pair of these flaps, such as 12, may be used to control the azimuth, while another pair, such as 13, may be used to control the range. Alternatively, in a simple form of such a device one pair of flaps, for instance 12, may be used as ailerons and the other two for steering purposes, such an arrangement resulting in control in one direction only. A remotely controlled bomb of this type is described in the aforementioned co-pending patent application of Wyckoff, Molnar, Palmer and Blewett, now U. S. Patent 2,466,528. The purpose of the ailerons is to maintain the axial roll orientation of the bomb. They may be controlled by means of a gyro, and operate so as to counter any tendency of the bomb to roll out of its proper orientation. In a bomb controlled in two directions the aileron action may be superimposed on the motion of either the rudders or elevators by means of appropriate interconnection of control linkages. The bomb may be equipped with contact fuze 14 and arming device 15. Devices 14 and 15 will be omitted on subsequent drawings of the invention since they form no part thereof per se.

In Fig. 2 the body of the bomb 10 is shown in the position of approximately 15° of both yaw and pitch. In this case, the line of flight as indicated by the arrow 16 from the center of gravity 17 is not in the direction of the axis of the bomb nor is it in the plane of any of the control surfaces. The control surfaces 11 experience a wind or air stream from the side such as indicated by arrow 18. The particular angular attitude such as here illustrated is the natural result of attempts to steer the bomb by means of rudders 12 and elevators 13, both rudder and elevator being applied simultaneously or in rapid succession. One may readily observe from this picture that while three of the control surfaces 11 are in the air stream 18, in general at least one control surface, such as 11', may be partially shadowed, so to speak, by the body of the bomb and therefore experiences much less aerodynamic force than the other surfaces 11. The result of this asymmetry is a torque tending to set up rotation of the bomb about its longitudinal axis 19, and such rotation ultimately results in complete confusion between rudder and elevator control. To eliminate such rotation of a bomb having a cruciform tail structure has been found to require prohibitively large and powerful ailerons.

Again referring to Fig. 1, while rudders 12 operate together so as to produce deflection of the bomb in the same direction, any inequality in their rudder effect results in the production of rotational torques about the longitudinal axis of the bomb. The same is true of inequalities in the elevators. Such inequalities in steering effect may result from partial shading of the lee steering surface when the bomb is in an attitude of yaw or pitch as shown in Figure 2, as well as from mechanical inequalities.

This invention is based on the discovery that by the use of a cylindrical stabilizing surface such as shown in Fig. 3 the tendency for axial

rotation of the bomb is substantially eliminated. Here the body of the bomb 10 is equipped with a tail structure having radial supports 20 holding a cylindrical surface 21. The bomb and its stabilizer surface 21 have cylindrical symmetry about the longitudinal axis 22. When such a cylindrically symmetrical surface 21 is given any combined yaw and pitch attitude, the area projected onto the wind stream direction is substantially invariant with roll orientation. Hence no rotational tendency arises from variation in projected area. Likewise any lift forces developed by the cylindrical surface 21, due to an imposed angle of attack, can only be exhibited as radial forces with no tangential components and no rotational tendency arises even if strong shading effects are present. Supports 20 and lift surface 21 may be streamlined according to good aerodynamic practice.

Fig. 4 illustrates a manner in which bomb of Fig. 3 may be steered to control its direction. The bomb body 10 equipped with the auxiliary cylindrical lift surface 21 held by radial supports 20 has, in addition, a cylindrical steering surface 23 supported on radial structure 24 mounted on gimbal or socket 25. An arm 26 connected to the steering surface support structure 24 is actuated by the control mechanism 27 housed inside the bomb. Mechanism 27 is directed by signals which are either remotely produced by the bombardier or originate in a target-seeking mechanism. The cylindrical steering surface 23 here acts to give the bomb the necessary yaw or pitch attitude to its line of flight such that the lift surface 21 produces the necessary and desired path deflecting force. Proper roll orientation is provided by means of ailerons 60 and 61 mounted on operating rods which are actuated in opposite directions by a gyro control mechanism 62 inside the bomb.

Fig. 5 shows another relative disposition of an auxiliary cylindrical lift surface 28 supported by radial structure 29 from the body of the bomb, whereas the smaller steering surface 23 may be supported and operated from the tail as in Fig. 4. This form of the invention has desirable characteristics in that the lift force available is augmented by that produced by the larger auxiliary cylinder 28 and is particularly advantageous if this auxiliary surface is located at or near the center of gravity of the bomb. In Fig. 5, automatically controlled ailerons 60 and 61 maintain the roll orientation of the bomb so as to provide proper identification of the steering direction, and the attitude of steering surface 23 may be controlled by arm 26 actuated through mechanism 27 as in Fig. 4.

In the construction of a steering surface mounting device such as indicated by 25 in Figs. 4 and 5, it is necessary to take into consideration hinge forces required to produce the necessary deflection of surface 23. These hinge forces may become considerable at high velocities, and it has been found desirable to separate rudder and elevator control into separately controllable functions instead of combining them on one surface, such as surface 23 of Figures 4 and 5.

Fig. 6 is a side view and Fig. 7 a tail end view of a bomb having circular lift surface 35 supported by radial struts 36, each of which has a tab 37 used for purposes of control. One may, for instance, use eight radial supports 36, two of these supports 36 being equipped with rudders 38, two being equipped with elevators 39, and the other four having ailerons 40. While such a structure

lacks perfect circular cylindrical symmetry, the lack of symmetry is relatively small and results in only small rotational forces easily handled by small ailerons 40.

5 The embodiment of Figs. 6 and 7 eliminates the roll tendency set up by shading of the lift surfaces, this being a large part of the rotational effect encountered in previously used bombs with flat-fin tail structure. However, rotational tendencies due to shading of the steering surfaces 38 and 39 may still be present and produce serious roll instability. These roll tendencies may be further eliminated by the use of the preferred disposition of steering surfaces shown in Figs. 8 and 9.

10 Fig. 8 shows the side view and Fig. 9 a tail end view of a preferred form of control surface in which a cylindrical lift surface 41 carries the rudders 42 and elevators 43. In order that steering elements 42 and 43 may have straight hinges for convenience in manufacturing, the lift surface 41 has the form of an octagonal cylinder thus permitting the insertion of steering tabs 42 and 43 in its straight portions. Rudders 42 and elevators 43 are connected by means of rods 44 and 45, respectively, to control mechanisms inside the bomb tail itself. Ailerons 46 may be placed on the radial supports 47 and operate to maintain the bomb in proper orientation. Details of the mechanism of a remotely controlled bomb of this type is described in aforementioned copending patent application of Wyckoff, Fitzwilliam and Salvetti, now U. S. Patent 2,495,304. Such a control surface as 41, while not having complete circular symmetry, has been found to be so nearly thereto that only small ailerons 46 are required to maintain orientation even though considerable yaw and pitch are set up by the steering elements 42 and 43. Furthermore, inequalities in the steering effects of elements 42 and 43 give rise to radial forces and not rotational forces, thereby eliminating any roll tendency from this cause.

15 Fig. 10 shows a side view and Fig. 11 a tail end view of a bomb having a circularly symmetrical auxiliary lift surface 48 connected to the body of the bomb through radial supports 49 and having a stabilizer and control surface 50 of octagonal shape and equipped with steering elements 51 and 52 similar to those of Fig. 9, ailerons 53 being provided to control the axial roll orientation as in Figs. 8 and 9. The use of a cylindrical lift surface such as 48 placed forward on the body of the bomb approximately at its center of gravity greatly increases the aerodynamic lift available and hence the maneuverability of the bomb is increased. Surface 48 may be increased in thickness to have the shape of a streamlined airfoil as shown in Fig. 10.

20 Figs. 12 and 13 show a bomb in which two control surfaces have been applied to the tail assembly in order to reduce the overall diameter, particularly at the bomb body. While in this case auxiliary lift surface 54 is not as effective as the surface 48 of Fig. 10, placed near the center of gravity of the bomb, there are other compensating advantages of reduced space. Rudders 55 and elevators 56 serve to steer this embodiment in a manner similar to that described in connection with Figs. 8, 9, 10 and 11, while ailerons 57 on radial support struts 58 serve to maintain orientation also as explained in preceding figures. Lift surface 56 may have the form of a circular shroud or may be octagonal in shape similar to surface 60. It has been found that lack of complete circular symmetry may be tolerated and the result-

7 small rotational forces may be overcome by use of moderately sized and moderately powered ailerons. Radial struts 58 and 59 represent the flat-fin cruciform effect but this effect may be minimized by keeping their size as small as possible and by angularly staggering struts 58 and 59 about the axis of the bomb.

My invention is not to be limited to the embodiments shown in the drawings as these are for purposes of example only. Any cylindrically shaped control and lift surfaces may be used, such shaped surfaces being effective in reducing roll angles which tend to throw the bomb out of control. While the cylindrical surfaces shown are the form of a cylindrical shell, the shell thickness may be increased and streamlined, as is generally done in such structures.

What I claim is:

1. An aerodynamic surface for a dirigible bomb comprising a surface having the form of a prismatic shell and having operable aerodynamic flaps mounted on and parallel to a straight portion of the trailing edge of said shell.
2. An aerodynamic surface for a dirigible bomb comprising a fixed surface having the form of a cylindrical shell affixed to the bomb and a second fixed surface having the form of a prismatic shell affixed to the bomb and having an operable aerodynamic flap mounted on and parallel to a straight portion of the trailing edge of said second fixed surface.
3. An aerodynamic surface for a dirigible bomb comprising a multiplicity of fixed surfaces each having the form of a prismatic shell affixed to the bomb and an aerodynamic flap operably mounted on and parallel to a straight portion at least one of said surfaces.
4. An aerodynamic surface for a dirigible bomb comprising a fixed surface affixed to the bomb and having the form of a cylindrical surface

5 whose thickness varies in the axial direction thereof in the manner of an airfoil and a second fixed surface affixed to the bomb and having the form of a prismatic surface whose thickness varies in the axial direction thereof in the manner of an airfoil and having an operable aerodynamic flap mounted on and parallel to a straight portion of said second surface.
